UNITED STATES PATENT OFFICE.

OSCAR C. RIXSON, OF NEW ROCHELLE, NEW YORK, ASSIGNOR TO THE OSCAR C. RIXSON CO., A CORPORATION OF ILLINOIS.

LOCK.

Application filed June 23, 1921. Serial No. 479,729.

To all whom it may concern:

Be it known that I, OSCAR C. RIXSON, a citizen of the United States, residing at New Rochelle, in the county of Westchester 5 and State of New York, have invented certain new and useful Improvements in Locks, of which the following is a full, clear, and exact description.

My invention has especial application to 10 mortice locks which are operated by a separate pin tumbler key operated lock, the tumbler lock with the key plug being exposed, usually in an escutcheon or other ornamental device, in the side of a door. In 15 most cases and particularly with outside doors, it is desirable for the sake of appearance to have the escutcheon or the exposed end of the key operated lock centrally located in the stile of the door. To satisfy 20 this requirement the dimensions of the lock must be such that the back set of the key mechanism, i. e., the distance from the key hole to the face plate, is substantially equal to half the width of the stile. It has therefore been necessary for supply dealers to 25 carry in stock several numbers of locks differing from each other essentially only in the distance between the face plate and key-operated lock.

30 An object of my invention is to provide a lock which may be adapted to various widths of stiles, thereby reducing the numbers of locks which a dealer must carry in stock, and in accordance with my invention 35 I make the back set of the key mechanism adjustable so as to bring the escutcheon into the desired relation to the stile of the door.

Preferably the angular disposition of the key mechanism is substantially unchanged 40 in any adjusted position, since it is desirable that the key slot should be vertical in the locked and unlocked positions of the key plug. Where, for instance, the adjustment is effected by an arcuate movement of the 45 key mechanism, a suitable connection may be provided between the key mechanism and the face plate which will permit of the arcuate movement of the shell while restraining it from rotative or angular movement.

50 My invention also comprehends various other features of construction which will appear more particularly from the description of the embodiment of my invention selected for the purpose of illustration and

shown in the accompanying drawings, in 55 which

Figure 1 is a side elevation of a complete mechanism embodying my invention;

Figure 2 is a rear elevation of the same; 60 Figure 3 is a longitudinal sectional elevation of the same on line 3-3 of Fig. 2;

Figure 4 is a transverse section of the supporting frame and shell on line 4-4 of Figure 1; and

Figures 5 and 6 are details in side and inner end elevation of the key mechanism.

The illustrated lock mechanism is of the type in which the face plate 1 is covered by a finishing and protecting plate or mask 2, usually of brass, which prevents access to 70 mechanism within the mortice in the door and minimizes the likelihood of unauthorized tampering with the lock. The housing of the mortice lock, consisting of the two cover or side plates 3 and 4, is secured to 75 the face plate 1 in any suitable way, as by screws 5. The bolt 6 is actuated by an operating member or lever 7 which protrudes through the top of the mortice lock housing and is itself operated by the key 80 mechanism, as will be hereinafter described. A latch member 8 is pivoted within a recess in the side of the bolt 6, being pivotally connected at its free end to the operating member 7. A flat spring 9 tends to hold the 85 latch 8 elevated with its two shoulders 8^a and 8^b behind a lug 10 on the cover plate 3 of the lock, in the unlocked and locked position of the bolt, respectively, and in throwing the bolt it is therefore necessary first to 90 depress the free end of the latch 8 sufficient to clear the lug 10.

The key mechanism consists of the usual cylinder pin tumbler lock 11 having an eccentric key plug on the inner end of which is 95 the cam or roll back 12. Only one of the key mechanisms is shown, although manifestly another may be employed on the opposite side of the door. To receive the key mechanism a shell 13 is employed, which has two 100 lateral trunnion projections bearing in circular openings in two parallel plates 14 and 15 secured together by rivets 16, as shown, and pivoted at their lower end by screws 17 to the mortice lock. They are further secured 105 together at their centers by a screw 18 which passes through an opening in the operating member 7 and serves as a fulcrum therefor.

The top edge of the cover plates 3 and 4 are of arcuate formation about the pivots 17 as a center throughout the range of movement of the fulcrum screw 18. Limiting stops 19 on the cover plate 3 determine the swinging movement of the plates 14 and 15 and the mechanism carried thereby.

The trunnion projections of the shell 13 are hollow and provided with internal screw threads into which are received the inner screw threaded ends of the key mechanisms 11. The key mechanisms are screwed within the shell until the end of the operating member 7 lies within the path of movement 15 of the roll back 12, and are then locked against rotation therein by the respective set screw 20 which engages in a groove in the side of the cylinder, one groove being provided in proper position in each side to make 20 the cylinder reversible. The face plate 1 is provided with a hole 21 opposite the heads of the set screws 20, which affords access with a proper tool to the set screws when the cover plate 2 is removed.

25 It is now manifest that by turning the key the roll back 12 is caused first to depress the member 7 to cause the latch 8 to clear the lug 10, and that the further movement of the roll back causes the member 7 to bear 30 against the fulcrum 18 and throw the bolt either in or out.

To swing the key mechanism upon the pivots 17 and vary its back set or distance from the face plate, a screw and nut mechanism is employed. The shell 13 is provided at its top with an elongated longitudinally extending nut 22 and a feed screw 23 engages in this nut and has its head bearing loosely in a counter-sunk hole in the face plate 1. By turning the screw 23 by means of a screw driver applied to either end the key mechanism is swung upon the pivots 17 and at the same time the cylinder and shell are held in substantially the same angular 45 position by reason of the long bearing of the screw in the lug or nut 22. The bearings therefore rotate about the trunnions as the parts are adjusted. Because of the relative thinness of the face plate the head of the 50 feed screw 23 has a certain freedom of movement which prevents binding of the parts. By the adjusting operation above described, it will be seen that the key hole of the lock can be located at the exact center 55 of the stile of the door thus making the lock of universal application to doors having different widths of stiles.

It is manifest that the invention is in no wise limited to any particular type of key mechanism, and in fact comprehends the combination with any lock operating mechanism, whether a door knob, thumbturn, bitted key mechanism, or other expedient.

60 It is obvious that various modifications

may be made in the construction shown and described within the principle and scope of my invention.

I claim:

1. A lock comprising, in combination, a lock case, a face plate carried thereby, a lock operating mechanism pivoted to the lock case and adjustable toward and from the face plate and operative in all positions 70 upon the lock.

2. A mortise lock comprising, in combination, a lock case, a face plate carried thereby a lock operating mechanism carried by the lock for operating the lock from either side of the door, said lock operating mechanism being adjustable relative to the lock toward and from the face plate and operative in all 80 positions upon the lock.

3. A lock construction for doors having a mortise and a transverse orifice communicating with the mortise from either side of the door, which construction comprises, in combination, a face plate and a bolt, a bolt operating mechanism adapted to be inserted through the transverse orifice from either side of the door, a support for the bolt operating mechanism constructed to receive the same from either side and adjustable independently of the bolt toward and from the face plate, said bolt operating mechanism when carried by the support being operative upon the bolt throughout the range of adjustment of said support.

4. In a lock, the combination of a lock case, a face plate carried thereby, a bolt, a lock operating mechanism exterior to the lock case having operative relation to the bolt, said operating mechanism being adjustable toward and from the face plate and operative in all positions upon the bolt.

5. The combination of a lock including a face plate, a lock operating mechanism adjustable toward and from the face plate, a bolt, a latch carried thereby, and an operating member having operative relation to the latch and lock operating mechanism throughout the latter's range of adjustment.

6. The combination of a lock including a face plate, a lock operating mechanism adjustable toward and from the face plate, a bolt, an operating member for the bolt having operative relation to the lock operating mechanism, and means actuated by the adjusting of the lock operating mechanism for keeping the operating member in operative relation to the bolt and lock operating mechanism throughout the latter's range of adjustment.

7. The combination of a lock, a face plate carried thereby, a lock operating key mechanism carried by the lock and adjustable relative to the lock toward and from the face plate, and means for effecting said adjustment, said means comprising a nut carried by the key mechanism and a feed screw en- 120

- gaging in the nut and bearing at one end in the face plate.
8. The combination of a lock, a face plate carried thereby, key mechanism for operating the lock, a support for the key mechanism pivoted to the lock, and an adjustable connection between the support and face plate.
9. The combination of a lock, a face plate carried thereby, a supporting member pivoted to the lock, a cylindrical key mechanism for operating the lock rotatively mounted in the supporting member, and an adjustable connection between the key mechanism and face plate adapted to adjust the supporting member upon its pivot while maintaining the key mechanism in substantially fixed angular position relative to the face plate during said adjustment.
10. The combination of a lock including a protruding operating member, a face plate attached to the lock, a supporting member pivoted to the lock, a cylindrical key mechanism rotatively mounted in the supporting member and having a cam member for engaging and actuating the said operating member within limits of pivotal movement of the supporting member, a threaded nut on the key mechanism, and a feed screw engaging the nut and bearing at one end in the face plate.
11. The combination of a lock including a protruding operating member, a face plate attached to the lock, a supporting member pivoted to the lock and having a bearing, a hollow cylindrical shell rotatable in said bearing and having a screw threaded nut
- integral therewith, a cylindrical key-operated lock carried by said shell and having a cam member for engaging and actuating the said operating member within limits of pivotal movement of the supporting member, and a feed screw engaging in the nut on the shell and bearing at one end in the face plate.
12. The combination of a lock including a protruding operating member, a face plate attached to the lock, a supporting member pivoted to the lock and having a bearing, a hollow cylindrical shell rotatable in said bearing and having a screw threaded nut integral therewith, a cylindrical key-operated lock carried by said shell and having a cam member for engaging and actuating the said operating member within limits of pivotal movement of the supporting member, the key-operated lock being rotatively adjustable in the shell, a set screw for securing the key-operated lock in the adjusted position in the shell, the face plate being provided with a hole opposite the set screw, and a feed screw engaging in the nut on the shell and bearing at one end in the face plate.
13. In a lock, the combination of a face plate, a key mechanism, a carrier for the key mechanism bodily movable towards and away from the face plate and means for securing the key mechanism in the carrier, the face plate having an opening affording access to said securing means.

In witness whereof, I hereunto subscribe my signature.

OSCAR C. RIXSON.
